CLAIM

I claim the ornamental design for a steering wheel lock, as shown and described.

DESCRIPTION

FIG. 1 is a bottom perspective view of a steering wheel lock showing my new design in the closed position with a steering wheel shown in broken lines and forming no part of the claimed design.

FIG. 2 is a front elevational view of the steering wheel lock shown in a partly open position.

FIG. 3 is a top plan view of the steering wheel lock.

FIG. 4 is a bottom plan view of the steering wheel lock.

FIG. 5 is a left side elevational view of the steering wheel lock;

FIG. 6 is a right side elevational view of the steering wheel lock; and,

FIG. 7 is a back elevational view of the steering wheel lock.
